(57) CLAIM

The ornamental design for a store facade, as shown and described.

DESCRIPTION

FIG. 1 is a front elevational view of a retail store facade showing my new design therefor;

FIG. 2 is a top sectional view taken along line 2—2 of FIG. 1 showing the contour of the facade;

FIG. 3 is a left side elevational view of the design of FIG. 1; and,

FIG. 4 is a right side elevational view of the design of FIG. 1.

The broken lines are for illustrative purposes only and form no part of the claimed design.
